UNITED STATES PATENT OFFICE

169,271

INFANT'S BATH SEAT

Beverly Jane McWaide, Seattle, Wash.

Application December 17, 1951, Serial No. 17,763

Term of patent 14 years

(Cl. D15—1)

To all whom it may concern:

Be it known that I, Beverly Jane McWaide, a citizen of the United States, and a resident of Seattle, in the the county of King and the State of Washington, have invented a new, original, and ornamental Design for an Infant's Bath Seat, of which the following is a specification, reference being had to the accompanying drawing, forming a part thereof.

In said drawing:

Fig. 2 is a bottom plan view thereof.

Fig. 3 is a side elevational view.

Fig. 4 is a front elevational view; and
Fig. 5 is a rear elevational view.

What I claim, is:

The ornamental design for an infant's bath seat, as shown.

BEVERLY JANE McWAIDE.
